PATENTED SEPT. 17, 1907.

J. C. RIGG.
LIFTING JACK.

APPLICATION FILED JUNE 3, 1907.

2 SHEETS-SHEET 1.

Fig. 2.

Technical drawing of a mechanical assembly, likely a component of a loom or similar textile machine. The drawing shows a top view of a frame structure with various parts labeled. Key components include a horizontal beam (1), a vertical post (2), a curved lever (3), and a series of heddle wires (4) passing over a comb (5). Other labeled parts include 6, 7, 8, 9, 10, 11, 12, 13, 14, 15, 16, 17, 18, 19, 20, 21, 22, 23, 24, 25, 26, 27, 28, and 29. The drawing is highly detailed, showing internal mechanisms and the interplay between different parts.

Fig. 1.

Technical drawing of a mechanical component, likely a part of the assembly shown in Fig. 2. This view shows a side or end perspective of a frame (1) with a vertical post (2). A curved lever (3) is attached to the frame. A series of heddle wires (4) are shown passing over a comb (5). The drawing highlights the mechanical linkage and the path of the wires through the comb. Other labeled parts include 6, 7, 8, 9, 10, 11, 12, 13, 14, 15, 16, 17, 18, 19, 20, 21, 22, 23, 24, 25, 26, 27, 28, and 29. The perspective view provides a clearer look at the spatial arrangement of the parts.

UNITED STATES PATENT OFFICE.

JAMES C. RIGG, OF HOOKTOWN, KENTUCKY, ASSIGNOR OF ONE-HALF TO J. H. COLLIER, OF HOOKTOWN, KENTUCKY.

LIFTING-JACK.

No. 866,221.

Specification of Letters Patent.

Patented Sept. 17, 1907.

Application filed June 3, 1907. Serial No. 377,097.

To all whom it may concern:

Be it known that I, JAMES C. RIGG, a citizen of the United States, residing at Hooktown, in the county of Nicholas and State of Kentucky, have invented certain 5 new and useful Improvements in Lifting-Jacks, of which the following is a specification.

This invention relates to lifting jacks of that type having a lever and a notched lifting bar, engaged by a pawl carried by the lever, and has for its object to improve 10 the construction of such jacks, particularly with respect to the manner of engaging or disengaging the pawl, and with respect to the means for adjusting the lifting bar according to the height of the wagon axle or other work to be hoisted.

15 The invention is illustrated in the accompanying drawings, in which

Figure 1 is a side elevation of the device. Fig. 2 is a similar view with the near side plate of the standard removed, with the parts in one position. Fig. 3 is a similar view with the parts in another position. Fig. 4 is a 20 horizontal section.

The standard of the jack is provided with a base 6 and consists of two side plates 7, preferably made of pressed steel or the like, spaced apart by spacing pieces or 25 blocks 8. These parts are bolted or otherwise fastened together securely, and the lifting bar and operating pawls are located in the space between the side plates.

The lifting bar is indicated at 9 and slides up and down at the rear edge against the rear spacing piece 8, 30 and it is provided with a head 10 of suitable form. On the front edge the bar has a rack 11 the teeth of which are hooked or inclined downwardly. The rack is sunken into the bar, between flanges 12 projecting at each side thereof, forming spaces 13 between said 35 flanges and the rack, as shown in Fig. 4. These spaces form guides for the pawl which engages the rack.

The operating lever is indicated at 14, fulcrumed on a bolt 15 at the top of the frame, between the side plates thereof, and this lever, which may conveniently be 40 made of wood, has metal side plates 16 which project at the lower end thereof, the pawl being swung or pivoted between said side plates by a bolt 17. The pawl consists of a pair of side plates 18 bolted together and spaced apart a proper distance to fit at their front edges in the 45 grooves 13 in the lifting bar, and they have extending therebetween a stout pin 19 in proper position to engage in any one of the notches in the ratchet. The pawl has a rearwardly-extending weighted arm 20 which normally holds the same in engagement with the rack, but 50 the pawl may be disengaged by lifting the weighted

arm, to swing the pawl out or back. To accomplish the same result in another way the ends of the plates 16 have projections 21 struck up inwardly therefrom, in proper position to engage behind the pawl plates 18 when the lever 14 is swung up toward the vertical. 55 When this is done the projections strike against the rear edges of the pawl plates and swing the plates out or forward in such position that the pin 19 will not catch in the notches, and so the lifting bar may be raised or lowered at will. 60

To control the drop of the lifting bar, a spring detent 22 is pivoted at 23 between the side plates and the standard and is arranged to engage in the notches of the rack, being normally held in a position to do so by a spring 24. This detent stops against a cross pin 25 thereunder, and 65 sustains the weight on the lifting bar when the lever is eased off. The detent projects through a slot in the spacing piece 8 at one edge of the standard, and has a treadle piece 26 so that it may be operated by the foot. Pressure on said treadle piece will lift the detent so that 70 it will not catch in the rack. This allows a quick drop of the lifting bar when desired.

In order to give a quick action or adjustment to readily accommodate the jack to wagons or work of different heights, a foot lever 27 is provided, fulcrumed at 28 75 near the base of the standard and projecting at its inner end under the foot of the lifting bar, its outer end being provided with a treadle so that it may be operated. When the lifting bar is down, it may be raised to any desired adjustment by pressing on the treadle of the 80 lever 27 which will raise the bar until the head thereof strikes the work. The detent 22 and the pawl at the head of the lever allow the necessary slip.

In operation, the lifting bar being adjusted to the work in the manner stated, the bar is raised by manipulation of the lever in an obvious manner. The detent 22 holds the weight after each stroke of the lever and the pawl slips down over the teeth, and is swung into engagement by the weight, for the next stroke. To lower the load, the detent is disengaged by pressing down on 85 its foot piece 26 after which the lever may then be eased off. For a quick drop, when not loaded, the detent is disengaged from the lifting bar, and the lever is swung up until the projections 21 strike the pawl and swing the same out of engagement with the bar, after which 90 the bar will drop by its weight to the lowest position. The bar may be quickly raised to adjustment by foot pressure on the lever 27, which will run the bar up to the desired height without any operation or movement of the hand lever. 95

I claim:

1. The combination with a lifting bar having a ratchet and grooves in the bar beside the ratchet, of a lever, and a pawl carried thereby and arranged to engage the ratchet and having side plates the edges of which fit in the grooves.
2. The combination of a standard, a ratchet lifting bar slideable up and down therein, a lifting lever fulcrumed on the standard and having a depending pawl hanging therefrom and adapted to engage the ratchet, a rear-

wardly extending weighted arm on the pawl, and a projection on the lever bearing against the upper edge of the pawl and adapted to disengage the same from the ratchet when the lever is swung up to inoperative position.

In testimony whereof I affix my signature, in presence 15 of two witnesses.

JAMES C. RIGG.
